CASE FILLING MACHINE

Allan C. Davis, Baltimore, Md., assignor to The
Davis Caser Company, Baltimore, Md., a cor-
poration of Maryland

Application April 13, 1951, Serial No. 220,747

20 Claims. (Cl. 226—14)

1

This invention relates to improvements in the case filling machine forming the subject matter of my copending application, Serial No. 192,210, series of 1948, filed October 26, 1950. More particularly the invention relates to improvements in the charge depositing mechanism and in the automatic control mechanism for the machine.

In the above application there was disclosed as one modification a mechanism for releasing articles from the charge depositing carriage involving rocking bars which were controlled by an arm fixed to one of the bars and a rack to transmit the rocking of the one bar to the other bars. The speed of release was dependent on the speed of lowering of the article depositing mechanism, since the arm was tripped by a plate in the path of the arm during the lowering of the depositing mechanism. This mechanism operates satisfactorily for light articles when the depositing carriage is lowered slowly but it is not so satisfactory for heavier articles since with them there is a tendency for the bars to release very rapidly with a "snap" action when the arm is partly rotated by the plate and for the charge of articles to "slam" into the case.

In order to overcome this tendency, there is provided as a feature of the present invention a piston and cylinder mounted on the article depositing mechanism, the rocking of the bars being permitted by the gradual exhaustion of the cylinder. There is thus accomplished a release which can be accurately controlled for different weight articles and which is independent of the speed of lowering of the depositing mechanism.

To still further accomplish a cushioning effect and gradual lowering of the bottles into the case, there is disclosed a modification having an improved expansible inverted frusto-conical rubber tube for cooperation with special stub spring fingers. This tube is more flexibly mounted and more sharply pointed than the tube disclosed in the prior copending application and the tube and stub fingers cooperate particularly advantageously with the piston and cylinder control in depositing heavy articles.

Further features of the present invention are improvements in the individual pockets, the means for mounting the pocket supporting frame and in the control circuit for the machine.

Other objects, features and advantages of the present invention will be apparent from the following description and accompanying drawings, in which:

Figure 1 is a left side elevation of a bottle case filling machine constructed like that in the above-

2

mentioned copending application except for the improvements forming the subject matter of the present invention.

Figure 2 is a partial fragmentary transverse sectional view at the front of the machine.

Figure 3 is a partial horizontal sectional view taken below the grid.

Figure 4 is a partial enlarged vertical sectional view illustrating the charge depositing mechanism or basket in upper charge receiving position, and in dotted lines in lower depositing position.

Figure 5 is a partial right side elevation of the basket in lower charge release position, almost at the end of downward movement.

Figure 6 is a diagrammatic view illustrating the electric control circuit for the machine.

Figure 7 is a partial transverse sectional view at the front of the machine illustrating a modified basket or bottle depositing mechanism.

Figure 8 is a top plan view of a single pocket removed from the basket of Figure 7.

Figure 9 is a partial longitudinal sectional view of the mechanism of Figure 7.

Figure 10 is a horizontal sectional view taken along the line 10—10 of Figure 9.

Figure 11 is a horizontal sectional view taken along the line 11—11 of Figure 9.

Figure 12 is a partial vertical sectional view taken along the line 12—12 of Figure 11.

Figure 13 is a partial transverse sectional view partly broken away, of the basket of Figure 7.

Figure 14 is a partial sectional view taken along the lines 14—14 of Figure 13.

In the drawings the same numeral refers to similar parts throughout the several views.

Briefly, referring to Figures 1 and 2, bottles B, being the articles with which the machine is described, enter the machine on the right side at the rear in a single line from a supply or conveyor 1. A delivery member or chain conveyor 2 having flights 3 receives a predetermined number of bottles into the compartments between each successive pair of flights in upright position and advances them forwardly over a charge collecting device comprising a grid 4 and an upper and lower stationary guide structure 5.

When the desired number of rows of bottles are on the grid to form a charge, longitudinal grid members or rails 6 of the grid are shifted laterally to position the bottles to drop through the grid vertically upon the further movement of the flight, into a charge receiving device or basket 7. The basket or receptacle is then lowered to deposit the bottles into a waiting receiver

or case C having partitions P, Figure 5, forming cells. The machine illustrated is entirely automatic, having control devices to initiate and coordinate the various steps in its operation.

The bottle feed conveyor 1 is driven by means of motor 8, Figure 6. The machine is illustrated as designed for four rows of six bottles in each row. As the sixth bottle of each row moves into a row in the chain conveyor 2 from the bottle conveyor 1, the first bottle on the left contacts a switch arm 9, Figure 6 (upper right), actuating a switch 10 to initiate intermittent movements, or steps of the chain conveyor 2. The mechanism for intermittently driving the chain conveyor 2 can be seen in Figure 1 and comprises a pneumatic cylinder 11 and piston 12. A pusher plate 13 which is adapted to engage the flights 3 is advanced by the piston 12 when pressure is admitted to cylinder 11 to advance the chain conveyor 2. When the cylinder 11 is exhausted, springs 14 retract the piston and pusher plate 13, and the pusher plate engages the next following flight 3, in readiness for the next advance. The cycle is then repeated.

In Figure 2 and in Figure 6 (upper left) is illustrated a switch lever 15 pivotally mounted to the right of the machine at the front of the grid 4. This lever is rotated by the sixth bottle of the first row as the chain conveyor 2 advances the fourth row of bottles onto the grid and actuates switch 16, Figure 6, to cause grid rails 6 to be shifted to allow the dropping of a charge of twenty-four bottles into basket 7, upon further movement of conveyor 2.

The basket 7 rides up and down on tracks 17 by means of lower rollers 18 mounted at the rear of the basket and rolling on the forward surfaces of the tracks and upper rollers 19 on the rear surfaces of the tracks. A cylinder 20 is mounted on the framework 21 which supports the machine. Piston rod 22 engages bracket 23, Figure 2, which is fastened to the U-shaped roller mounting plate 24 of carriage 24 of the basket 7.

After the charge of bottles is dropped from the grid into the basket, the cylinder 20 is exhausted to lower the basket to position above a case. The conveyor for moving cases into position beneath basket 7 is seen in Figure 3 and comprises a roller conveyor 25 driven by motor 26 (Figure 6). A table comprising the rollers 27 in the machine extends rearwardly beneath the basket 7 further than supply conveyor 25 so as to extend in width to discharge rollers 28, offsetting the discharge from the feed. The case enters the machine guided by side rail 29 toward the front of the table and strikes case stop abutment plate 30, closing switch 31 to actuate the case positioning mechanism. This case positioning mechanism includes cylinder 32 and case pusher 33 attached to the piston in the cylinder, and the pusher is moved longitudinally from front to rear across the table by the piston and cylinder 32. After the case is filled with a charge of bottles, cylinder 32 is exhausted, case pusher 33 is retracted across the table by springs 34 and the case leaves the machine at the left on the discharge rollers 28, the case temporarily depressing a second case abutment plate 35 to open switch 36 and prevent the case positioning mechanism from operating until the filled case has cleared the table.

In the foregoing description, those parts of the case filling machine which necessarily cooperate with the improvements of the present invention or are necessary to a complete understanding of the present invention have been set

forth. For a more detailed description of the machine, reference may be had to the aforementioned copending application.

The carriage 24 includes an angle member 37 forming the rear and sides of the carriage and ledges 38 and 39 on the sides of the member 37 mount the pocket frame front and rear cross supports 40 extending from left to right across the basket. Intermediate cross supports 41 are fastened to longitudinal end plates 42 and center plate 43, the end plates in turn being carried by the front and rear cross supports 40 complete the pocket frame. Twenty-four pockets 44 are mounted between the cross supports, as illustrated in Figure 3, and are spaced in accordance with the cells of the case to be filled. The pockets comprise small rectangular frames, each having outwardly curving bottle guiding ears or flanges 45 on all four sides and right angle pocket supporting lips 46 on the front and rear sides of the individual frames, Figure 2. The pockets are held in the large pocket frame by means of set screws 47 and plates 49 each pressing a set of three pockets suspended between adjacent cross supports and against center plate 43. Spring urged pin 50 and bolt and nut 51 (Figure 2) hold the assembled pocket frame in the carriage, the nut of nut and bolt 51 bearing against the front of front cross support 40 to keep it from sliding forwardly on ledges 38. To remove the pocket frame, the nut and bolt 51 are removed, the pin 50 is retracted and the assembled pocket frame is pulled out of the carriage, the front and rear cross supports 40 sliding forwardly on ledges 38 and 39.

Mounted on the frame of each pocket are left and right inwardly bent springs 52 and front and rear straight springs 53. The front and rear springs 53 are adapted to be bent inwardly as shown in Figure 1, 2, 3 and 4 by means of rocking bars 54. These bars are cylindrical with laterally expanded, flattened portions 55 engaging the straight springs 53. A cylinder 56 is mounted on the carriage by pin 57 and bracket 59. The piston 60 is connected to a crosspiece 61 having head 61 thereon. Springs 62 extend between the crosspiece 61 and bracket 59 to retract the piston. A shaft 63 is carried by head 61 and operates crank 64 which is fixed to the front rocking bar 54, at the right of the basket. At the left the other bars 54 are connected for rocking with the front bar by means of cranks 65 and connecting arm 66.

The operation of the machine and the improvements in the control circuit of the present invention will now be readily understood.

Power is supplied to the machine by supply conductors 70, 71. Conductor 71 is designated with a plus sign and conductor 70 with a minus sign for convenience in following the operating circuits of the solenoids. When the operating switch 72 is closed, the bottle conveyor motor 8 and the case conveyor motor 26 are set in motion through conductors 73 and 74. When six bottles have entered the chain conveyor 2 between flights 3 and switch arm 9 has been actuated to close switch 10, the chain conveyor cylinder air inlet valve operating solenoid 75 is operated by the circuit from "plus" conductor 74 through conductor 76 (center, Figure 6), manual chain conveyor stop switch 77, chain conveyor air inlet valve operating solenoid 75, strap 79, conductor 80, switch 10 (upper right, Figure 6), conductor 81, switch 16 (top contacts) to "minus" conductor 73. Solenoid 75 raises armature 82, raising lever 83 to open valve 84 to air supply line

85. Air then enters chain conveyor cylinder 11 through pipe 86 and flow adjustment valve 87.

The pusher plate 13 is then advanced to step the conveyor and bolt 89 carried by plate 13 contacts pin 90 of switch 91 to open the switch at the end of the step. As soon as flights 3 advance, switch 10 opens by the passage of the bottle from arm 9. The holding circuit for solenoid 75, to insure the completion of the step of conveyor 2, extends from strap 79 through switch 92, which is closed by arm 93 on the raising of armature 82, through conductor 94, switch 91, conductor 95 to the "minus" conductor 73. This circuit is broken by the opening of switch 91 and solenoid 75 releases, opening the exhaust 96 of valve 84 to exhaust cylinder 11 to retract the pusher plate, by springs 14.

When the first row of bottles of a complete charge reaches lever 15, Figure 2, at the front of the machine, the lower contacts of switch 16, Figure 6, are closed and the upper ones opened. The grid shifting solenoid 97 is then energized from "minus" conductor 73, through switch 16, conductor 99, solenoid 97, conductor 100, switch 101, when closed, conductors 102, 103 to "plus" conductor 74. As seen in Figures 2 and 6, a pin 104 is bolted to the right side of the carriage 24. When the basket is in upper charge receiving position, this pin contacts roller 105 of switch lever 106 mounted on the frame of the machine, to close switch 101. Thus the grid can only be shifted when the basket is in proper upper position, and switch 101 is closed. When the grid 4 has shifted, blade 107 carried by the grid moves between roller 105 and pin 104 to hold switch 101 closed and the grid shifted as long as switch lever 15 is contacted by a bottle. When the charge has dropped through the grid and has cleared it properly, switch lever 15 will clear the main body of the bottle and rotate to the position shown in Figure 6 to open the lower contacts of switch 16 to release solenoid 97, so that grid 4 can return to its charge receiving position. It will be understood that the chain conveyor cannot be stepped while the upper contacts of switch 16 are open.

The above described part of the control circuit is similar to that in my copending application.

The case positioning cylinder 32 is energized by a case depressing abutment plate 30, Figure 6, lower right, to close switch 31. The "minus" supply conductor 78 then connects through conductors 109, 110, switches 36, 31, conductor 111, case pusher solenoid 112, and conductor 103 to the "plus" supply conductor 71, operating the solenoid 112. Armature 113 is raised to open valve 114 to air supply 85 to position a case.

The raising of arm 115 of valve 114 by armature 113 also raises intermediate link 116 connected to the arm, which in turn closes the upper contacts of switch 117 (lower left, Figure 6). The basket raising cylinder solenoid 119 was being held energized through its holding circuit extending from "plus" supply conductor 71 through conductor 120, solenoid 119, strap 121, holding switch 122, conductor 123, the lower contacts of switch 117, conductor 124 and conductor 109 to the "minus" supply conductor 78. This circuit is opened when switch 117 is operated by the case positioning solenoid 112 and elevating solenoid 119 is deenergized exhausting cylinder 20 through pipe 125, flow adjustment valve 126 and exhaust 127 of valve 129.

At this point in the operation, the rocking bar cylinder 56 is under pressure by virtue of the

energization of solenoid 130 through "minus" conductor 73, switch 131, conductor 132, solenoid 130, conductors 133 and 76 to "plus" conductor 74.

Referring to Figures 1, 2, 3, and 4, the switch 131 is controlled by roller arm 134 acting on plate 135 mounted at the rear of carriage 24 on the left side. At a predetermined point in the downward travel of the basket 7, the plate 135 disengages from arm 134, and switch 131 is opened. This deenergizes solenoid 130 allowing armature 136 to lower, opening exhaust 137 of valve 139. Cylinder 56 is then exhausted through flexible hose 140, flow adjustment valve 141 and exhaust 137. The speed of release of the charge by the spring fingers 53 may be positively controlled for any weight bottles independently of the speed of descent of the carriage 24 by flow valve 141. The point of descent of the carriage to initiate the exhaustion of cylinder 56 is controlled by the proper construction of plate 135 and the positioning of switch arm 134.

When the basket has reached its lower position and cylinder 56 is sufficiently exhausted to have permitted the release of the charge into a case, as in Figure 5, the switch 142, Figure 4, is actuated by the curved end 143 of connecting arm 66 contacting roller arm 144 of the switch. This opens the right contacts of switch 142 (center left, Figure 6), deenergizing case pusher solenoid 112, to release the filled case from the machine by opening the holding circuit through conductor 111, strap 145, holding switch 146 and conductor 147. Switch 142 also operates the basket raising solenoid through its left contacts, conductor 149 and strap 121.

When the basket is raised, arm 134 contacts plate 135 closing switch 131, and in turn closing the basket fingers to hold another charge.

The modification of Figures 7 through 14 necessitates no changes in the carriage, large pocket frame, or charge release cylinder and these parts being identical to the parts previously described are given the same reference numerals. Reference is made to the description in connection with Figures 1 through 6 for an understanding of the operation of these parts.

The pockets of the embodiment of Figures 7 to 14 have small rectangular frames as previously, but fixed to the four sides of each frame is the elongated top 159 of the improved expansible rubber tube 151 of this invention. The tube is freely suspended from the pocket frame and is molded about the modified rocking bars 152 as indicated at 153 to promote the even hanging of the tube Figure 8. Openings 154 in the tubes admit the spring finger actuating blades 155. Curved stub spring fingers 156 are mounted on the left and right sides of the pocket frames, outside the frames, between the tube and the pocket and stub straight fingers 157 are similarly mounted at the front and rear of the pockets. The lower part of each blade 155, as seen in Figure 9 is slightly longer than the upper in order to obtain equal inward deflection of the front and rear straight spring fingers 157.

The inverted frusto-conical expansible portion 159 has a sharply pointed end comprising separate inwardly sloping folded points 161, Figures 9 and 12. These folded points are continuous with folds 160 when viewed from within the tube as shown in Figure 10, but make possible the expansion of the tube from a very sharp point to the maximum cross-section of the articles to be passed therethrough. This sharply pointed tube has a special advantage in connection with

the filling of collapsible cardboard cartons of the type commonly used for carrying six bottles, where there is more tendency for the bottle receiving openings to be out of line. The pointed tube tends to move the openings into alignment to receive the charge of bottles and to direct the bottles toward the openings.

The special advantage of the present improved tube is its flexibility, being suspended from the very top of the basket. This is important as a safety feature. In the practical operation of the machine, the operator, in case of difficulty, may pull the case being filled out of the machine and then look for the difficulty. With the flexibly suspended tube, this results in no tearing of the tube or damaging of the bottles even if the basket has not raised properly.

The stub fingers in this modification are controlled in their release in a manner similar to that of the longer fingers. However, additional cushioning effect is now accomplished by the expandable tube. The stub fingers of the present embodiment promote perfect centering of the bottles and release a charge of bottles uniformly and surely, as well as gradually, independent of the speed of lowering of the basket. The gradual release of the bottles into the tubes has a tendency to promote better centering of the bottle cardboard cartons and the like by the tubes. The present flexibly suspended sharply pointed tubes are not likely to foul on the partitions of a case or to be injured when a case is pulled out before the basket has been properly raised.

What is claimed as new and is desired to be secured by Letters Patent is:

1. In an article packing machine for filling a cell case with a charge of articles, a charge depositing mechanism and means for delivering a charge to said mechanism, said mechanism comprising a carriage movable between charge receiving and charge release position, a plurality of pockets in the carriage to correspond to the cells of a case, means in each pocket to retain an article therein, said retaining means being movable between article retaining and release positions, means to effect said movement means for guiding the movement of said carriage from charge receiving to charge release position, and a piston and cylinder mounted on said carriage and connected to said effecting means to control the release of said article retaining means in releasing articles from said pockets.

2. In an article packing machine for filling a cell case with a charge of articles, a charge depositing mechanism and means for delivering a charge to said mechanism, said mechanism comprising a carriage movable from upper charge receiving to lower charge release position, and a plurality of pockets in the carriage to correspond to the cells of a case, means in each pocket to retain an article therein, said retaining means being movable between article retaining and release positions, means to effect said movement and a piston and cylinder carried by said carriage and connected to said effecting means to control the release of said article retaining means, to release articles from said pockets in lower carriage position, said piston and cylinder operating said article retaining means, to set the same to retain articles in the pockets in the upper carriage position.

3. In an article packing machine for filling a cell case with a charge of articles, a charge depositing mechanism and means for delivering a charge to said mechanism, said mechanism com-

prising a carriage movable from upper charge receiving to lower charge release position, and a plurality of pockets in the carriage to correspond to the cells of a case, means in each pocket to

5 retain an article therein, said retaining means being movable between article retaining and release positions, means to effect said movement and a piston and cylinder carried by said carriage and connected to said effecting means to

10 control the release of said article retaining means to release articles from said pockets in lower carriage position, said piston and cylinder operating said article retaining means to set the same to retain articles in the pockets in the upper carriage position and means disposed intermediate upper and lower positions of said carriage actuated by the movement of said carriage to exhaust the cylinder as the carriage is lowered to gradually release said article retaining means.

15 20 4. In an article packing machine for filling a cell case with a charge of articles, a charge depositing mechanism and means for delivering a charge to said mechanism, said mechanism comprising a carriage movable from upper charge

25 receiving to lower charge release position, and a plurality of pockets in the carriage mounted in rows and columns to correspond to the cells of a case, movable converging fingers beneath each pocket to retain an article therein means

30 in the carriage to move the fingers between positions of article release and retention and pneumatic means mounted on said carriage and connected to said moving means to release said fingers from converging position to release articles

35 from the pockets in lower carriage position, and to restore the fingers to article retaining position after the release of articles from the pockets.

5. In an article packing machine for filling a cell case with a charge of articles, a charge depositing mechanism and means for delivering a charge to said mechanism, said mechanism comprising a carriage movable from upper charge receiving to lower charge release position, and a plurality of pockets in the carriage mounted in rows and columns to correspond to the cells of a case, fingers beneath each pocket, means in the carriage to move the fingers between positions of article release and retention, pneumatic means mounted on said carriage and connected to said moving means to operate said moving means, to release the fingers from article retaining position in lower carriage position and to restore the fingers to article retaining position after the release of articles from the pockets.

cles from said pockets in lower carriage position, said piston and cylinder operating said holding means to hold the fingers in converging relation to retain articles in the pockets in the upper carriage position.

7. In an article packing machine for filling a celled container with a charge of articles, a charge depositing mechanism comprising a carriage movable from upper charge receiving to lower charge release position, a plurality of pockets in the carriage mounted in rows and columns to correspond to the cells of a container, a bar rotatably mounted in said carriage and extending between adjacent pockets, spring fingers mounted with said pockets in the carriage and depending from the pockets adjacent said bar and having an article release position, means on said bars contacting said fingers and pressing said fingers into said pockets to obstruct the pockets and hold articles therein in one position of said bar, and pneumatic means connected to said bar to control the rocking of the bar to and from pocket obstructing position.

8. In an article packing machine for filling a celled container with a charge of articles, a charge depositing mechanism comprising a carriage movable from upper charge receiving to lower charge release position, a plurality of pockets in the carriage mounted in rows and columns to correspond to the cells of a container, a bar rotatably mounted in said carriage and extending between adjacent pockets, spring fingers mounted with said pockets in the carriage and depending from the pockets adjacent said bars, the fingers having an article release position, means on said bars contacting said fingers and pressing said fingers into said pockets to obstruct the pockets and hold articles therein in one position of said bar, and a piston and cylinder mounted with said carriage for movement therewith and connecting with said bar to control the rocking of the bar to and from pocket obstructing position.

9. In an article packing machine for filling a celled container with a charge of articles, a charge depositing mechanism comprising a carriage movable from upper charge receiving to lower charge release position, a plurality of pockets in the carriage mounted in rows and columns to correspond to the cells of a container, a bar rotatably mounted in said carriage and extending between adjacent pockets, spring fingers mounted with said pockets in the carriage and depending from the pockets adjacent said bars, the fingers having an article release position, means on said bars contacting said fingers and pressing said fingers into said pockets to obstruct the pockets and hold articles therein in one position of said bar, and pneumatic means connected to said bar to control the rocking of the bar to and from pocket obstructing position, means for raising and lowering said carriage and means actuated upon the rocking of said bar to press the fingers to article obstructing position to actuate the raising means for said carriage.

10. In an article packing machine for filling a celled container with a charge of articles, a charge depositing mechanism comprising a carriage movable from upper charge receiving to lower charge release position, a plurality of pockets in the carriage mounted in rows and columns to correspond to the cells of a container, a bar rotatably mounted in said carriage and extending between adjacent pockets, spring fingers mounted with said pockets in the carriage and

depending from the pockets adjacent said bars, the fingers having an article release position, means on said bars contacting said fingers and pressing said fingers into said pockets to obstruct the pockets and hold articles therein in one position of said bar, and a piston and cylinder mounted with said carriage for movement therewith and connecting with said bar to control the rocking of the bar to and from pocket obstructing position, means for raising and lowering said carriage and means actuated by the rocking of said bar in releasing the articles to actuate the raising means for said carriage.

11. In an article packing machine for filling a celled container with a charge of articles, a charge depositing mechanism comprising a carriage movable from upper charge receiving to lower charge release position, a plurality of pockets in the carriage arranged in rows and columns to correspond to the cells of a container, a bar rotatably mounted in said carriage and extending between adjacent pockets, spring fingers mounted with said pockets in the carriage and depending from the pockets adjacent said bars, the fingers having an article release position, means on said bars contacting said fingers and pressing said fingers into said pockets to obstruct the pockets and hold articles therein in one position of said bar, and pneumatic means connected to said bar to control the rocking of the bar to and from pocket obstructing position, means for positioning a container below said carriage and means actuated by the rocking of said bar in releasing the articles into the container to release the container positioning means.

12. In an article packing machine for filling a celled container with a charge of articles, a charge depositing mechanism comprising a carriage movable from upper charge receiving to lower charge release position, a plurality of pockets in the carriage arranged in rows and columns to correspond to the cells of a container, a bar rotatably mounted in said carriage and extending between adjacent pockets, spring fingers mounted with said pockets in the carriage and depending from the pockets adjacent said bars, the fingers having an article release position, means on said bars contacting said fingers and pressing said fingers into said pockets to obstruct the pockets and hold articles therein in one position of said bar, and a piston and cylinder mounted with said carriage for movement therewith and connecting with said bar to control the rocking of the bar to and from pocket obstructing position, means for positioning a container below said carriage and means actuated by the rocking of said bar in releasing the articles into the container to release the container positioning means.

13. In an article packing machine having a pneumatic cylinder for raising and lowering a charge depositing mechanism and a pneumatic cylinder for positioning a case in charge receiving position beneath the depositing mechanism, and valves to admit pressure to said cylinders, and electro-magnetic means to operate the valves, and a holding circuit for the electro-magnetic means operating the charge depositing cylinder valve, the improvement comprising a link connected to the electro-magnetic means actuating the valve controlling the pressure for said case positioning cylinder, a switch operated by said link in the holding circuit for maintaining the charge depositing cylinder under pressure with the mechanism in raised position, the actuation

11

of said case positioning cylinder to position a case moving the valve and link to open the holding circuit switch to exhaust the charge depositing cylinder to lower the charge depositing mechanism to the case.

14. In an article packing machine for filling a celled container with a charge of articles, a charge depositing mechanism comprising a carriage movable from upper charge receiving to lower charge release position, a plurality of pockets in the carriage mounted in rows and columns to correspond to the cells of a container, a bar rotatably mounted in said carriage and extending between adjacent pockets, spring fingers mounted with said pockets and depending therefrom adjacent said bars, the fingers having an article release position, means on said bars contacting said fingers and pressing said fingers into said pockets to obstruct the pockets and hold articles therein in one position of said bar and a rubber tube having an elongated top suspended from the top of each pocket with the fingers within the tubes, and the tubes having an opening therein for admitting the finger contacting means on said bars, said tubes having inverted frusto-conical expandable bottoms.

15. In an article packing machine for filling a celled container with a charge of articles, a charge depositing mechanism comprising a carriage movable from upper charge receiving to lower charge release position, a plurality of pockets in the carriage mounted in rows and columns to correspond to the cells of a container, a bar rotatably mounted in said carriage and extending between adjacent pockets, spring fingers mounted with said pockets and depending therefrom adjacent said bars, the fingers having an article release position, means on said bars contacting said fingers and pressing said fingers into said pockets to obstruct the pockets and hold articles therein in one position of said bar and a rubber tube having an elongated top suspended from the top of each pocket with the fingers within the tubes and the tube having an opening therein for admitting the finger contacting means on said bars, said tubes having inverted frusto-conical expandable bottoms and pneumatic means connected to said bar to control the rocking of the bar to and from pocket obstructing position.

16. In an article packing machine, for filling a celled container with a charge of articles, a charge depositing mechanism comprising a carriage movable from upper charge receiving to lower charge release position, a plurality of pockets in the carriage mounted in rows and columns to correspond to the cells of a container, a bar rotatably mounted in said carriage and extending between adjacent pockets, spring fingers mounted with said pockets and depending therefrom adjacent said bars, the fingers having an article release position, means on said bars contacting said fingers and pressing said fingers into said pockets to obstruct the pockets and hold articles therein in one position of said bar and a rubber tube having an elongated top suspended from the top of each pocket with the fingers within the tubes and the tube having an open-

12

ing therein for admitting the finger contacting means on said bars, said tubes having inverted frusto-conical expandable bottoms and a piston and cylinder mounted with said carriage for movement therewith and connecting with said bar to control the rocking of the bar to and from pocket obstructing position.

17. A carriage for a charge of articles, to hold articles and to release them therefrom, partitions in the carriage dividing the carriage into a plurality of pockets, flexible article holding fingers depending from the top of the pockets, the fingers having an article release position, rubber tubes enclosing the fingers and depending from the top of each of the pockets, means to bend the fingers to article holding position and to release them therefrom.

18. A carriage for a charge of articles, to hold articles and to release them therefrom, partitions in the carriage dividing the carriage into a plurality of aligned pockets, flexible articles holding fingers depending from the top of the pockets, certain of the fingers being on one side of the pockets and being aligned with each other, the fingers having an article release position, rubber tubes enclosing the fingers and depending from the top of each of the pockets, a rod extending adjacent the aligned fingers on one side of the pockets having means thereon to bend the fingers to article holding position and to release them therefrom, the rubber tubes having openings therein to admit the finger bending means.

19. In an article packing machine for filling a celled container with a charge of articles, a charge depositing mechanism comprising a carriage movable from upper charge receiving to lower charge release position, a plurality of pockets in the carriage mounted in rows and columns to correspond to the cells of a container, said pockets comprising rectangular frames having at the tops thereof outwardly curved flanges for guiding articles into the pockets.

20. In an article packing machine for filling a cell case with a charge of articles, a charge depositing mechanism having a plurality of pockets therein and means for guiding articles vertically through said depositing mechanism to a case comprising an open resilient hose in each pocket attached at its upper periphery to the edges of the pocket, the lower end of each hose being resiliently vertically fluted to restrain an article passing therethrough, the extreme lower end of the flutes being pointed downwardly toward the axis of the hose to fit into the cell of a case, the flutes expanding upon the release of an article through the pocket to a case and then again contracting.

ALLAN C. DAVIS.
